UNITED STATES PATENT OFFICE.

ANTON J. ROLLERT, OF CHICAGO, ILLINOIS, ASSIGNOR TO THEODORE A. KOCHS, OF SAME PLACE.

BARBER'S CHAIR.

SPECIFICATION forming part of Letters Patent No. 464,588, dated December 8, 1891.

Application filed November 15, 1890. Serial No. 371,567. (No model.)

To all whom it may concern:

Be it known that I, ANTON J. ROLLERT, a citizen of the United States of America, residing at Chicago, in the county of Cook and State of Illinois, have invented certain new and useful Improvements in Barbers' Chairs, of which the following is a specification, reference being had therein to the accompanying drawings.

10 This my invention relates to barbers' chairs, with the object in view to provide a chair the seat of which will rotate on its base, and in which the back and foot-board are so connected by the arm-rests that they will swing 15 in unison from a vertical to a nearly-horizontal position, and in which by the swinging of a single hand-lever the seat can be locked to be rigid with its base and the back and foot-board can be locked on any inclining position; 20 and with these objects in view my invention consists of the novel devices and combinations of devices hereinafter described and specifically claimed.

In the accompanying drawings, Figure 1 represents a side elevation of the chair with its back and foot-board adjusted to be in almost horizontal positions. Fig. 2 is a longitudinal vertical section of the pivot portion of the chair; Fig. 3, a sectional plan view of the same 30 on line 44 of Fig. 2. Fig. 4 is a transverse vertical section of the pivot portion, and Fig. 5 a rear elevation of the same.

Corresponding letters of reference in the several figures of the drawings designate like parts.

A denotes the base of the chair, consisting of a central hub *a*, having secured four curved straddling legs *b*. The hub *a* is vertically bored through its center for securing therein metal socket *c*, bored out cylindrically and having at its top a horizontal annular flange *d*, provided on its outer edge with a vertically-projecting cylindrical rim *e*, that is internally faced and bored to be concentric with the bore of socket *c*. Into this socket *c* is snugly fitted the cylindrical tubular stem *f*, expanded on its upper portion to provide a cylindrical box or chamber *g*, that has horizontal flanges *h* at its upper edge, bolted under the chair-seat *B*. The side rails of seat *B* have at their ends upward projections, form-

ing the pivotal connections for the back *C* and the foot-board *D*, both again pivotally connected by the arm-rests *E* in a manner that a reclining movement of the back will 55 swing the foot-board upward, and vice versa, and to the end of the foot-board *D* is connected the adjustable foot-cushion *F*.

Diametrically through box or chamber *g* of tubular stem *f* is bored a hole, which is screw-tapped for engaging the screw-threaded portion of the shaft *i*, having secured upon its end the lever *j* to be exterior of the chair-seat at one side thereof, with its upper handle in easy reach for the barber, standing behind the chair, to grasp it with his right hand. Upon the middle of this screw-threaded portion of shaft *i* is rigidly mounted an eccentric *K*, to be inside the box or chamber *g*, vertically over the tube of stem *f*, and into this tube is inserted a pin *l*, that with its bottom end will rest upon the bottom of socket *c*, while its top end will be in contact with eccentric *K*, so the entire weight of the chair-seat and occupant can be supported on such 75 pin *l* and carried by the eccentric *K*, and that the barber by swinging the lever *j* in a forward direction will turn the eccentric *K* to lift the seat, and by swinging the lever *j* in a rearward direction the seat will be lowered again, the entire vertical movement being very limited.

In the shallow socket inside of rim *e*, upon flange *d* of socket-casting *c*, is snugly fitted a ring *m*, so as to turn therein easily. This ring *m* is split at one side to provide a radial slot *n*, while diametrically opposite the slot *n* the ring *m* has inside a notch *o*, that will enable it to be sprung apart and to contract again as soon as released, and against the 85 rear side of the box or chamber *g* of tubular stem *f* is rigidly secured by screws a wedge *p*, which enters slot *n* of ring *m* in a manner that by lowering the seat, by swinging the lever *j* rearward, the wedge *p* will expand the 90 ring *m* against the inner peripheral face of rim *e* to afford by frictional contact a rigid hole therein, and that by lifting the seat, by swinging the lever *j* forward, the wedge will be raised sufficiently to allow the ring *m* to 95 contract again and then to turn loosely with the seat. This device, as will be readily seen,

operates like a brake controlled by the vertical movement of the chair-seat on its base. Under foot-board D is secured a rigid arm q, having pivotally connected to its end one end of a bar r, longitudinally slotted from its opposite end to near its middle, and this slotted portion is placed over the screw-threaded projecting end of shaft i to slide thereon, and exteriorly of this slotted bar r is secured upon the screw-threaded end of shaft i a nut s and a jamb-nut t with a washer u intermediate of bar r and nut s. Upon rotating shaft i, by swinging lever j, the said shaft i must laterally follow its screw-thread in a manner that with the swinging of such lever in a rearward direction the washer u will be moved against bar r, clamping the same against box or chamber g and holding it rigidly, while by swinging lever j forward the bar r will be released again, the nuts s and t enabling a very accurate adjustment for such clamping device. It will be understood that when not clamped by the above device the bar r is free to slide on the end of shaft i while swinging the back and foot-rest, but when clamped said bar r will form a rigid brace for holding the back and foot-rest in any desired position relative to the seat.

From the above it will be readily seen that with the lever j swung to its forward position the seat will easily turn upon its pivot by swinging the lever j to its vertical position, the chair-seat will be held from turning by the expansion of ring m, caused by the gravity of the chair-seat forcing the wedge p into slot n of such ring, and with swinging the lever j to its rearward position the back C and foot-board D will be locked and rigidly held on their vertical or any inclining positions that may be desirable without releasing the seat for a turning movement on its base. It will also be readily noticed that the occupant of the chair, without the assistance of the barber, can adjust the position of the parts by the motion of his body, and can then handle the lever j for locking the parts to be sustained in such relative positions.

What I claim is—

1. A chair comprising a base, which rests at all times upon the floor or other support and at all times supports the seat independently of any other means of support, a socket-piece mounted upon said base, a vertically-movable seat having a downwardly-projecting hollow stem located within and supported upon said socket-piece, a pin located within and supported upon said socket-piece, an eccentric carried by and connected with said seat and acting upon said pin for raising and lowering the seat, and devices for operating said eccentric, substantially as shown and described.

2. A chair comprising a base, a vertically-movable seat having a pivotal connection therewith, and a brake device for preventing the rotation of the seat, embracing two members, one of said members being carried by the seat and the other member being carried

by the base, and said members being located to rigidly engage each other when the seat is at the lower limit of its movement and to be disengaged from each other when the seat is elevated, substantially as shown and described.

3. A chair comprising a base, a vertically-movable seat having a pivotal connection with said base, a split ring located within a socket on said base, and a wedge carried by said seat and engaging said split ring.

4. A chair comprising a base, a vertically-movable seat having a pivotal connection with said base, a friction-ring located within a socket on said base and having separated end portions, and a wedge carried by said seat and engaging the separated end portions of said friction-ring.

5. A chair comprising a base, a vertically-movable seat having a pivotal connection therewith, devices for raising and lowering said seat, and a movable foot-board connected with and controlled by said devices for raising and lowering said seat.

6. A chair comprising a base, a vertically-movable seat having a pivotal connection therewith, devices for raising and lowering said seat, and a movable foot-board adjustably connected with said devices for raising and lowering said seat.

7. A chair comprising a base, a vertically-movable seat having a pivotal connection therewith, devices for raising and lowering said seat, and a movable foot-board having a sliding connection with said devices for raising and lowering the seat.

8. A chair comprising a base, a vertically-movable seat pivotally supported thereon, an eccentric carried by said seat and acting upon said base, a shaft for operating said eccentric, and a movable foot-board adjustably connected with said shaft.

9. A chair comprising a base, a vertically-movable seat pivotally supported thereon, an eccentric carried by said seat and acting upon said base, a shaft for operating said eccentric, having screw-threaded connection with said seat, a movable foot-board, and a bar connected with said foot-board and having a sliding connection with said shaft and located between the seat and an abutment on said shaft.

10. A chair comprising a base, a seat having a stem located within a socket in said base, an eccentric carried by said stem and acting upon said base, a shaft for operating said eccentric, having a screw-threaded connection with said stem, a movable foot-board, and a bar having a sliding connection with said shaft, said bar being located between an abutment on said shaft and the said stem and being pivotally connected with said foot-board.

11. A chair comprising a base, a seat having a stem located within a socket in said base, an eccentric carried by said stem and acting upon said base, a shaft for operating said eccentric, having a screw-threaded connection

with said stem, a movable foot-board, and a bar having a slotted portion embracing said shaft, said slotted portion being located between an abutment on said shaft and the 5 said stem, and said bar having a pivotal connection with said foot-board.

12. A chair comprising a base, a vertically-movable seat having a pivotal connection therewith, devices for raising and lowering 10 said seat, a movable foot-board pivoted to said seat and connected with and controlled

by said devices for raising and lowering said seat, side rails pivoted to said foot-board, and a chair-back pivoted to said seat and to the said side rails.

15

In testimony whereof I affix my signature in presence of two witnesses.

ANTON J. ROLLERT.
